UNITED STATES PATENT OFFICE.

HELEN HANFORD, OF DOWNSVILLE, NEW YORK.

DESIGN FOR A MEAT-POUNDER AND BONE-CUTTER.

57,334.

Specification for Design.

Patented Mar. 15, 1921.

Application filed July 5, 1918. Serial No. 243,490. Term of patent 3½ years.

To all whom it may concern:

Be it known that I, HELEN HANFORD, a citizen of the United States, residing at Downsville, in the county of Delaware and State of New York, have invented a new, original, and ornamental Design for a Meat-Pounder and Bone-Cutter, of which the following is a specification, reference being had to the accompanying drawing, forming a part thereof.

Figure 1 is a perspective view of a meat pounder showing my new design.

Fig. 2 is a side elevational view of the same.

I claim:

The ornamental design for a meat pounder and bone cutter, as shown.

HELEN HANFORD.

Witnesses:

EDWARD E. CANLON,
LULU WAYSTAFT.
